UNITED STATES PATENT OFFICE

RAYMOND E. GARVEY, OF IRONWOOD, MICHIGAN

HEATING SYSTEM

Application filed October 13, 1928, Serial No. 312,247, and in Canada November 30, 1927.

This invention relates to heating systems. An object of this invention is to provide an improved heating system wherein a boiler construction such as is shown in my United States Patent No. 1,672,252, granted June 5th, 1928, may be enlarged upon whereby heat which may radiate through the boiler casing may be subjected to a controlled circulation of air, and the heated air delivered to any desired point.

Other objects and advantages of the invention will become apparent during the course of the following description.

In the drawings I have shown one embodiment of the invention. In this showing,

Figure 1 is a vertical sectional view, parts being shown in elevation,

Figure 2 is a section on line 9—9 of Figure 1, and

Figure 3 is a horizontal section on line 10—10 of Figure 1.

Referring to the drawings the numeral 10 designates an ordinary furnace, preferably of the oil or gas burning type. The furnace 25 is provided in its front end with a fire door 11 and an ash pit door 12. Clean out doors 13 of the usual type also are provided to permit the flues of the furnace to be cleaned out. The furnace is provided with a stack or 30 outlet pipe 14 adapted to be controlled by the usual damper 15.

Outer and inner metal casings 16 and 17 surround the top, sides and back of the furnace in spaced relation thereto as clearly 35 shown in Figures 1 and 3. The casings 16 and 17 form in effect a single casing having parallel walls slightly spaced, and this space may be utilized either as a dead air space or may be filled with heat insulating material 40 as indicated at 18. The forward end of the casing is provided with an inwardly extending wall 19 snugly fitting against the sides of the furnace adjacent the front thereof whereby the latter is accessible in the usual 45 manner for firing the boiler or furnace. At the sides of the furnace a relatively narrow passage 19' is provided inwardly of the casing, and this passage extends throughout the height of the furnace. Rearwardly of the 50 furnace, a relatively deep space 20 is provided

and this space communicates with an outlet pipe 21 closed at its outer end by a cap 22. A branch pipe 23 connects the pipes 21 and 14 and may be controlled by a suitable damper 24.

Inwardly of the casing, a horizontal plate 25 surrounds the furnace adjacent the top thereof, and below the plate 25 another plate or partition 26 extends from the rear end of the casing to a point spaced from the forward end thereof as indicated at 27, whereby the passage 19' is divided into passages or flues 28 and 29. As shown in Figure 2, the plates 25 and 26 extend from the back of the furnace to the back wall of the casing.

Means are provided for permitting the flue gases to pass into the passage 28 instead of passing directly to the stack. For this purpose, branch pipes 30 are connected with the stack 14 and extend into opposite sides of the space between the plates 25 and 26, rearwardly of the furnace. Dampers 31 are adapted to control the passage of gases through the pipes 30 and these dampers are controlled by handles or knobs 32.

The elements and arrangement thereof which have been described are substantially similar to the showing in my United States patent previously referred to and form no part of the present invention except in combination with the features and elements to be next described.

The present invention relates to a novel arrangement preferably for use with the structure previously described by the employment of which any heat which may be radiated from the boiler jacket may be carried by a circulation of air to desired points such as rooms of a building, thus using the radiated heat for heating purposes. The structure previously described is provided with another casing comprising inner wall 70 and outer wall 71 surrounding the furnace and so arranged as to provide a passage 72 between this outer casing and the casing defining the space 18 previously described as filled with a suitable heat insulating material. The space between inner wall 70 and outer wall 71 may be filled with a suitable heat insulating material or may be simply left as a dead air space 100.

as desired. Above the furnace the outer casting formed by the walls 70 and 71 is shaped to form a hood 73, at the rear end of which a pipe 74 provided with a damper 75 is connected. The pipe 74 extends above the floor line indicated as at 76 through a wall of one of the rooms of the structure in the basement of which the heating device is arranged. A chamber designated generally by the numer-
10 al 77 is arranged adjacent the bottom of the passage 72. A horizontal partition 78 forming the top of chamber 77 is provided with a series of openings 79 which may be of any desired shape but varying in area so that the
15 opening located at the point where air from pipe 80 enters the chamber, is of the smallest area. The pipe 80 is connected at one end to the chamber 77 and at its opposite end to one of the rooms located above the floor line of
20 the structure in which the heating device is located. Pipe 80 is provided with damper 81 and is also provided with a branch pipe 82 in which a damper 83 is arranged. A damper 84 is also provided in pipe 80 above the point
25 of connection of pipes 80 and 82. A pipe 85 is connected at one end to pipe 74 adjacent the lower end of the latter, and at its opposite end leads to the chimney 37. A pipe 86, the lower end of which is flanged outwardly leads
30 from the space adjacent the smoke pipe 14 to the pipe 85 connected to the chimney. Dampers 87 and 88 are arranged in pipes 85 and 86 respectively.

The operation of the device is as follows:
35 As previously stated, the system is particularly adapted for use in connection with heating plants employing oil or gas burning equipment but is not necessarily limited to such use. The operation of the furnace per-
40 se is substantially similar to the operation disclosed and explained in my patent previously referred to and need not be referred to again in detail.

In the operation of the air circulation to
45 convey heat radiated from the boiler casing, if it is desired to supply heat to a room located above the floor line 76, damper 87 is slightly opened and damper 75 located in pipe 74 is opened so as to allow the
50 desired amount of heat to be carried into the room. With damper 87 slightly open the draft created by the chimney 37 will cause air to be admitted into the upper end of pipe 80, provided dampers 84 and 81 are open, and the air so admitted will enter the chamber 77 and be distributed equally around the furnace by means of openings 79 and pass up the sides of the furnace between walls 16 and 70 absorbing any heat which
55 may have radiated through the insulated space 18. This heated air flows to the top of the furnace where it is directed by the hood 73 into the pipe 74, from whence a portion of the thus heated air passes upwardly
60 through pipe 74 and is delivered through
65

opening 74' into the room which it is desired to heat.

This heating system also is adapted to cause a circulation of air in the basement or room in which the heating device is located in order that foods and vegetables may be kept in the same room with the heating device without spoiling due to any heat which otherwise might be radiated from the heating system. Such a circulation of the air adjacent the heating system is caused by opening dampers 83, 81 and 87, and closing damper 75. When the dampers are so arranged the draft caused by the chimney draws air through pipes 82, 80, chamber 77, hood 73, pipes 74 and 85 into the chimney.

Any heat which may radiate from outlet pipe 14 is carried from the space adjacent the pipe through pipes 86 and 85 into the stack, thus preventing excess heating of the outlet pipe.

The size of the parts is designed so that in all cases damper 87 in pipe 85 may be left partially open in order to form a draft and thus cause a circulation of the air drawn into chamber 77 through pipe 80, whether damper 75 be open or closed.

The arrangement thus shown, in addition to furnishing a supply of heated air which may be admitted to a room to heat the same, also acts to keep the inner casing formed by the walls 16 and 17, cool, thus preventing their burning out.

It is to be understood that the form of the invention herewith shown and described is to be taken as a preferred example of the same and that various changes in the shape, size and arrangement of parts may be resorted to without departing from the spirit of the invention or the scope of the subjoined claims.

I claim:

1. In a device of the character described, a boiler provided with a boiler casing, a second casing arranged in spaced relation to said boiler casing forming a chamber surrounding a portion of said boiler, a pipe having one end opening into a space which it is desired to heat and being connected at its opposite end to the chamber formed by said boiler casing and said second casing, a smoke stack for said boiler, a second pipe connected at one end to said chamber and having its opposite end opening into the space which it is desired to heat, said second pipe being provided with an opening communicating with said smoke stack and adapted to cause a circulation of air within said chamber, to transfer and deliver the heat radiated through said boiler casing to the space desired to be heated.

2. In a device of the character described, a boiler provided with a boiler casing, a second casing arranged in spaced relation to said boiler casing forming a chamber sur-

rounding a portion of said boiler, a distributing chamber arranged adjacent said first named chamber and surrounding a portion of said boiler, openings of different areas formed in a portion of said distributing chamber and affording communication between said two chambers, a pipe arranged with one end opening into a space which it is desired to heat and connected at its opposite end to said distributing chamber at a point adjacent the openings of smallest area; a smoke stack connected with said boiler, a second pipe connected at one end to said first named chamber and having its opposite end opening into the space which it is desired to heat, said second pipe being provided with an opening communicating with said smoke stack and adapted to cause a circulation of air within said chamber, to transfer and deliver the heat radiated through said boiler casing to the space desired to be heated.

In testimony whereof I affix my signature.
RAYMOND E. GARVEY.
